LEO SIMMONS, OF WASHINGTON, DISTRICT OF COLUMBIA.

AIR-VALVE FOR RADIATORS.

1,182,430.

Specification of Letters Patent.

Patented May 9, 1916.

Application filed March 6, 1915. Serial No. 12,687.

To all whom it may concern:

Be it known that I, LEO SIMMONS, a citizen of the United States, residing at Washington, District of Columbia, have invented 5 certain new and useful Improvements in Air-Valves for Radiators, of which the following is a specification.

This invention relates to certain improvements in air valves for radiators; and the 10 objects and nature of the invention will be readily understood by those skilled in the art in the light of the following explanation of the accompanying drawing illustrating what I now believe to be the preferred embodiment or mechanical expression of my invention from among other formations and constructions within the spirit and scope thereof.

An object of the invention is to reduce 20 leakage of water from radiator air valves to the minimum, and also to render such valves approximately noiseless.

The invention consists in certain novel features in construction and arrangements as 25 more fully and particularly set forth and specified hereinafter.

Referring to the accompanying drawings: Figure 1, is a perspective view showing part 20 of a radiator having an air valve of my invention applied thereto. Fig. 2, is a sectional view on an enlarged scale, taken in the plane of the line 2—2, Fig. 1. Fig. 3, is a detail section taken in the plane of the line 3—3, Fig. 2. Figs. 4 and 5, are detail 25 perspective views.

In the drawings, I show part of a steam or other heating system radiator 1, although 40 my invention is not limited to use in connection with any particular heating radiator type or construction. The rear end of such radiator is provided with a tapped hole 2, opening into the interior of the radiator to receive a valve to permit escape of air from the interior of the radiator under the pressure 45 of the heating fluid in said radiator.

The valve of my invention comprises a horizontally-elongated casing 3, forming a preferably cylindrical chamber 4, and provided with an upwardly projecting enlargement or boss 5, on which is mounted a cap or cylinder 6, as more fully described herein- 50 after.

The inner end of the casing 3, is formed integral with a reduced longitudinally-projecting exteriorly-threaded nipple 7, adapted to screw into and close the perforation

2, into the radiator. This nipple is formed with a reduced preferably tapered nozzle or inlet end 8, forming a longitudinal continuation of the nipple projecting therefrom a 60 suitable distance into the interior of the radiator so that the extremity of this nozzle will be spaced from the inner surfaces of the radiator walls.

An air inlet duct 9, extends longitudinally 65 throughout the lengths of the nozzle and nipple and at its discharge end opens centrally into the inner end of the chamber 4, of the casings, while at its inlet end said duct opens through the reduced or pointed end 70 of nozzle 8. The nozzle is designed to reduce to the minimum possibility of water entering the nozzle from the interior of the radiator. The nozzle is formed to prevent water of condensation collecting there- 75 on and being carried into the duct 9, with the air or vapor. The water of condensation usually collects on the inner surfaces of the radiator walls, and hence I have provided the nozzle to locate the inlet of duct 9, 80 remote from the radiator walls to prevent, so far as possible, water flowing or creeping into said duct from the radiator surfaces.

Within the chamber 4, I arrange a block 85 or cylinder 10, of any suitable material such as hard rubber, that will expand and contract under changes in temperature, and I provide the block with needle valve 11, fixed to the block and projecting longitudinally therefrom into the enlarged inner end portion 90 of air duct 9. The outer end of this valve is adapted to approximately close said duct against flow of fluid by closing outwardly against valve seat 12, formed in the duct intermediate the length thereof. The 95 block 10, longitudinally fits within the chamber 4, throughout the greater portion of the length thereof and conforms to the interior shape of the casing 3, so as to permit but a film like flow of fluid between the exterior 100 surface of the block and the interior surface of the casing 3. It might be said that the block has a running fit within the casing leaving but an almost infinitesimal fissure between its exterior surface and the casing 105 for passage of fluid in the casing from duct 9.

The outer end of the casing 3, is internally tapped to receive the removable threaded sealing plug 13, having an angular projecting rear end to which a suitable tool can be fitted for applying and removing the plug.

A valve adjusting and block-stop screw 14, extends through this plug and is longitudinally adjustable therein and at both ends projects beyond the same so that the inner 5 end of the screw can abut the outer end of the valve controlling block 10, and so that the outer end of the screw can receive a suitable tool for rotating and thereby adjusting the screw. The block 10, and the plug 13, 10 are arranged to leave a comparatively small or narrow fluid space or chamber within the casing and between the block and plug.

The boss or neck 5, is formed with a longitudinal duct 15, extending vertically there- 15 through and at its lower end having a preferably reduced inlet port 16, opening into the top of said fluid chamber at the rear end of block 10, while the upper end of said duct opens upwardly and preferably centrally 20 through the usually flat top face of said boss. The cylindrical upper end of said boss is preferably threaded to removably receive the internally threaded lower end of the open-bottom vertical cap or cylinder 6, 25 having a dome-shaped upper end that is closed except for a restricted outlet, preferably, formed by an exceedingly small or narrow horizontally elongated fissure or slit 19, opening vertically through the top end wall 30 18, of said cap. The top end wall 18, is preferably very thin with respect to the side walls of the cap, being reduced in thickness for the reason hereinafter appearing.

The cap is preferably exteriorly formed 35 with an exterior enlargement 22, by which the cap can be readily rotated when applying or removing the same to or from the boss 5.

The cap contains a series of comparatively 40 thin metal disks 20, piled or stacked one on the other and each having an edge notch 21, or other formation to permit upward leakage of air through the stack of disks to the fluid chamber within the dome like upper 45 end of the cap. The top end of the boss 5, is formed with an annular open top well or deep groove 17, with its open top immediately below the lower disk 20, of the stack, to form a water trap.

50 After the valve has been applied to a radiator, the thermostatic controlled needle valve is not adjusted until the radiator and air valve parts have become thoroughly heated and the block 10, has consequently expanded approximately to its limit, thereupon the screw 14, is adjusted inwardly against the outer end of block 10, to force the needle 11, inwardly against its seal 12, to approximately prevent outflow of steam 55 from the radiator. When the block 10, cools and contracts, the needle valve 11, will be withdrawn sufficiently from seat 12, to permit free outflow of air from the radiator. 60 This air will leak through casing 3, along 65 the exterior surface of the block 10, and flow

slowly or under reduced pressure into the chamber 4, at the rear end of said block. From said chamber, the air will escape upwardly through the reduced port 16, into the duct 15, from which it will flow into the cap or cylinder 6, and gradually work its way laterally between the disks 20, and upwardly past the edges thereof, and finally will escape in a thin comparatively slowly moving film to the atmosphere through the 70 elongated slit 19, in the top wall of the cap. 75

The fissure between the block 10, and the inner surface of the casing 3, is designed to subject the fluid leaking therethrough to a maximum exposure to the hot surfaces of 80 the block and casing for the purpose of vaporizing water of condensation, and furthermore to retard the flow of such fluid to reduce the pressure thereof when entering the space in the casing at the rear of the block. 85 The outlet port 16, is from the top of said space and is designed to prevent upward passage of free water or water of condensation from the casing 3, and hence said casing forms a trap to retain free water and 90 subject the same to the heated surfaces of the casing and the bodies therein for the purpose of vaporizing the same. The air or air and vapor flowing upwardly through duct 15, will also be subjected to the vaporizing influence of the heated neck or boss 5, which is formed by a substantial body of metal. The metal disks 20, also become highly heated and hence serve to vaporize moisture that might collect in cap 6, so that 100 the fluid that issues from outlet 19, will be in the form of comparatively dry air or vapor. Any moisture that collects in the cap 6, will flow down onto the boss 5, and into the trap 17, to prevent the same being 105 discharged as free water through the outlet 19. The moisture in trap 17, will be subjected to the vaporizing influence of the substantial body of hot metal forming the boss 110 or neck 5. The disks 20, are usually similar and can be stamped from suitable (preferably non-corrodible) sheet metal and rest loosely on each other. Each disk is preferably stamped out with a single very small notch in its edge and the stamping process 115 usually slightly dishes the disks or forms depending feather edges so that faces of the disks will not tightly adhere but will permit films of fluid to flow there between and upwardly through said notches. The disks are usually so arranged that the notches of adjacent disks are out of alignment. If so desired, each disk will be formed with a slight depression or bulge to engage on an adjacent disk, whereby the disks will be maintained 120 slightly separated from the flow of fluid therebetween.

The disks are usually slipped snugly into the cap but are not secured therein except as they may be upheld therein by the screw 130

threads at the lower end of the cap when the cap is removed, but even then the disks are preferably removable from the cap. These disks retard the upward flow of the fluid so that when the fluid reaches the outlet 19, its pressure has been reduced to such an extent as to escape without objectionable noise and without carrying water.

The objects of the invention are to prevent discharge of water from the outlet 19, and also to permit the discharge of dry air or vapor from said outlet without objectionable noise. In this connection, I wish to point out that I have discovered that by forming the outlet 19, by a very narrow elongated slit, whistling or other objectionable noise is avoided even where the air escapes under heavy pressure. Also, danger of condensation of the existing vapor is avoided by reducing the thickness of the top wall of the cap 5 when the outlet opening.

It will be noted that when there is minus pressure in the radiator, *i. e.* when the pressure in the radiator is below that of the atmosphere, the exterior pressure will drive the block 10, inwardly and seat the needle valve to prevent rush of cool air into the radiator. However, the needle valve is preferably so formed, about as shown, to prevent the same wedging or sticking against its seat and in closed position. Also, when there is minus pressure within the radiator, the exterior pressure tends to hold the disks 20, downwardly and tightly together to retard or reduce passage of cool air downwardly through duct 15. A radiator will hold its heat for a maximum length of time, even when the pressure therein is minus, where the cool exterior air is excluded, or approximately excluded, from the interior of the radiator.

It is evident that various changes, departures, omissions, additions, and modifications might be resorted to without departing from the spirit and scope of my invention and hence I do not wish to limit myself to the exact disclosure hereof.

What I claim is:

1. An air valve for radiators comprising a horizontally elongated casing at one end having a longitudinally projecting nipple adapted to screw into a radiator and having a duct extending longitudinally therethrough and forming the air inlet from the radiator into the casing and containing a valve seat, an expansion block arranged longitudinally in said casing and movable therein, said block at its inner end provided with and carrying a longitudinally projecting needle valve entering said duct and adapted to close against said seat on inward movement of said block, said casing having a space in the rear of said block and a lateral outlet from said space, and said block

adapted to be forced inwardly on increasing air pressure in said space thereby closing said duct.

2. An air valve for radiators comprising a casing at one end having a projecting nipple adapted to screw into a radiator, said nipple provided with a longitudinal duct having its inlet at the outer end and its outlet opening into said casing, a valve seat formed in said duct, an expansion block in said casing and movable therein, said block provided at its inner end with a needle valve adapted to close against said valve seat in said duct, and means at the outer end of said casing, at the rear of said block, whereby said block and valve are forced inwardly closing said duct when the radiator pressure is minus.

3. An air valve for radiators comprising a casing having an elongated nipple at one end provided with a longitudinal duct therethrough opening into said casing, an expansion block in said casing and movable therein, said casing having a space at the rear of said block and a vertical outlet passage therefrom, means carried by said block for closing said duct when the pressure in said space forces said block toward said duct.

4. An air valve for radiators comprising a casing having an air inlet adapted to be placed in communication with the interior of a radiator, an expansion block longitudinally movable within said casing and at one end provided with a needle valve fixed thereto and projecting therefrom into said air inlet, and adapted to close and open the same on the expansion or contraction of said block, said casing provided with a space having a vertical outlet at the rear of said block whereby said block is moved forward by the entering air when there is minus pressure in the radiator thereby closing said inlet, and means carried by the casing and separate from the block limiting the outward movement of said block in said casing.

5. An air valve for radiators comprising a casing at its inner end having an inlet duct adapted to receive air from the radiators to which the casing is applied, an expansion block longitudinally arranged in the casing and provided with and carrying a needle valve to close said duct on expansion of the block and to open said duct on contraction of the block, said block providing a thin fissure between its outer surface and the inner surface of the casing for leakage of fluid in the casing past the block, said casing having an upper lateral fluid outlet in rear of said block, a plug closing the outer end of the casing, and a block engaging and adjusting screw carried by said plug and operative from the exterior of the casing.

6. An air valve for radiators comprising a casing at one end having a nipple to enter

- a radiator and an inlet duct to receive fluid from the radiator, said casing having a lateral neck rising therefrom and containing the outlet duct from the top of the interior 5 of the casing, a cap on said neck forming a chamber into which said outlet duct discharges and having a top restricted fluid outlet, a needle valve for closing and opening said inlet duct, an expansion block in 10 said casing and controlling said valve and obstructing the fluid passage through said casing, and means in said cap to obstruct the fluid flow therethrough.
7. An air valve for radiators having an 15 inlet for fluid from the radiator and a remote outlet to atmosphere and an obstructed tortuous fluid passage way from said inlet to said outlet, and a pile of closely arranged metal disks arranged in said passage way.
- 20 8. An air valve for radiators comprising a casing embodying a horizontal portion having an air inlet to receive air from a radiator, and a vertical portion having a top air outlet and a bottom air inlet from the 25 upper portion of said horizontal portion, a thermostatically controlled valve in said horizontal portion controlling said air inlet thereto, and means in said vertical portion to heat and obstruct the flow of air passing 30 therethrough.
9. An air valve for radiators comprising a casing having an air inlet and a vertical portion having a top air outlet, and a stack of closely arranged horizontally disposed metal 35 disks partially filling the interior of said vertical portion, substantially as described.
10. An air valve for radiators comprising a casing having a vertical portion containing a stack of approximately parallel en- 40 gaging notched metal disks, said stack of disks being arranged in the air passage through the casing, substantially as described.
11. An air valve for radiators comprising 45 a casing having a vertically disposed neck with an air duct therethrough, a cap on the neck forming a chamber into which said duct discharges, said cap having a top out- let to the atmosphere, the upper end of said neck formed with a moisture trap, and means in said cap to prevent direct upward flow of air therethrough.
12. An air valve for radiators comprising a casing having an air inlet and a vertical portion having a top air outlet formed by a narrow horizontally elongated slit opening vertically therethrough, and a stack of approximately parallel engaging notched metal disks, said disks being arranged in the air passage for the purpose substantially as set forth.
13. An air valve for radiators comprising a horizontally disposed portion, an elongated extension from said portion having an air inlet therethrough, a vertical portion having its top formed by a reduced wall and having an air inlet through said wall formed by a narrow slit, a thermostatically controlled valve in said horizontal portion and a stack of closely arranged horizontally disposed metal disks partially filling the interior of said vertical portion.
14. An air valve for radiators comprising a horizontally disposed member, an elongated nozzle extending therefrom having a valve seat therein, a thermostatically controlled needle valve within said horizontal portion and operating on the valve seat in said nozzle, valve adjusting means in one end of said member, a vertical portion extending upwardly from said member having a centrally located passage and a water trap around said passage at its upper end, a cap for said portion having a reduced top wall and an elongated narrow slit therethrough forming an air outlet and a stack of approximately parallel engaging notched metal disks arranged in said cap and occupying a portion thereof.
